J. A. MALARKEY.
 COMBINED KITCHEN AND IRONING TABLE,
 APPLICATION FILED FEB. 14, 1921.
1,424,418. Patented Aug. 1, 1922.

UNITED STATES PATENT OFFICE.

JAMES A. MALARKEY, OF PORTLAND, OREGON.

COMBINED KITCHEN AND IRONING TABLE.

1,424,418.

Specification of Letters Patent. Patented Aug. 1, 1922.

Application filed February 14, 1921. Serial No. 444,691.

To all whom it may concern:

Be it known that I, JAMES A. MALARKEY, a citizen of the United States, and a resident of the city of Portland, county of Multnomah, and State of Oregon, have invented a certain new and useful Improvement in Combined Kitchen and Ironing Tables, of which the following is a specification.

For economy of space and the convenience of the user it is desirable to provide a table which may be arranged to serve either as an ordinary table or as an ironing table, and which may as readily be folded up into a compact parcel.

Furthermore it is desirable to provide an ironing table which may be conveniently disassembled for shipment or storage and when received by the dealer or purchaser as readily and easily set up again.

It is therefore the object of my invention to provide a table which may be arranged to serve in either of the capacities mentioned, which may be folded up into compact form and which, besides the numerated features may be inexpensively made.

I attain my object in the device illustrated in the accompanying drawings, and herein-after described.

Referring to the drawings,

Fig. 1 shows a perspective view of my table with all its leaves extended;

Fig. 2 shows a perspective view of my table arranged as an ironing board or table;

Fig. 3 shows an end elevation of my table when arranged as shown in Fig. 2;

Fig. 4 shows a longitudinal fragmentary section of the ironing board end of my table, the section being taken at the near side of the guide blocks in which the arm of the leg supporting the ironing board leaf slides when in its extended position;

Fig. 5 shows the separable parts of my table and illustrates how convenient it is to pack the same; and

Fig. 6 is a fragmentary perspective detail of the under side of that end of the table top to which the ironing board leaf is attached.

The frame of my ironing table is composed of a top board or table top *a* removably supported on standards *b* and *c* for the latter are respectively provided with cleats *r* having perforations as *v* and *u* for insertion of the screws.

The lower portions of the standards *b*, *c*, are connected by a brace bar *d* provided on its under side with cleats *n* which brace the

bar *d* adjacent the standards *b* and *c*, and preferably the standards *b* and *c* are provided with grooves *t* and *s* respectively in which the ends of the brace bar *d* are inserted, in this way obtaining a more rigid construction. The standards *b* and *c* terminate at the bottom in feet as *p* and *q*. Leaves *e* are removably connected to each of the sides of the table top *a* by separable hinges *f*. The leaves are supported when extended by leg frames *g* hinged by dowel pins *w* between the table top *a* and the brace bar *d*.

A leaf or ironing board extension *h* shaped like the end of an ironing board is removably hinged at one end of the table top. For supporting the ironing board extension in horizontal position I provide a leg *i* having an arm *j* which slides in the slot *k* of the standard *b* and between the guide blocks *k'* on the under side of the table top *a*. In order to prevent the arm *j* of the leg *i* being accidentally drawn entirely out of the slot *k* a pin as *m* is inserted through one of the holes *y* of said arm *j*.

When it is desired to use the ironing board extension *h* it is first lifted and the leg *i* is pulled out sufficiently to securely support the same.

Since the table top *a* is made just the width of the ordinary ironing board the edges of the extension *h* form a continuation of the edges of the table top and thus these parts together form a complete ironing board of ample length. When so arranged my table will appear as shown in Fig. 2 and of course if a large piece of goods is to be ironed the leaves *e* may be lifted to their extended position as illustrated in Fig. 1.

When it is desired to use my table as an ordinary table one or both of the leaves *e* may be extended as usual and supported by the legs *g* being swung out as shown in Fig. 1 and the ironing board extension *h* being dropped down out of the way, or it may be supported in extended position as a part of the table if desired.

As apparent from the illustration and description my table may be easily taken apart and set up again by the mere use of a screw driver. When taken apart or knocked down the parts of my table may be assembled as illustrated in Fig. 5.

In a companion application for patent entitled "Knockdown folding table," filed Feb. 14, 1921, under Serial No. 444,692 I

am covering my invention as relating to the knock down table and my present application is confined to the ironing board feature of my table.

5 The illustrations and description above given are merely intended to show a practical mode of construction of my device. The particular details of construction above described are, however, variable to suit the 10 ideas of the manufacturer, provided such variation retains the essential features of my invention.

I claim:

In a combined table and ironing board, 15 the combination of a central portion comprising end standards, one of which is provided at its upper end with a recess, a brace connecting the lower portion of the standards, a top of greater transverse width than 20 the transverse width of the standards to provide overhanging portions, spaced cleats on the underside of the top adjacent the recess, the space formed between the cleats communicating with and forming a continuation 25 of the recess, a leaf hinged to each over-

hanging portion, foldable legs pivotally mounted between the brace and the top to support the leaves when extended, an ironing board having one end equal in width to the width of the top and hinged to the latter 30 adjacent the standard having the recess, a leg having a horizontal extension at its upper end, said extension fitting in the recess and spaced between the cleats and adapted to be withdrawn for the leg to support the ironing board when in use, said leg being housed in the space formed by the ironing board when the latter is not in use, the table top and the adjacent standard, and a pin in the extension to limit the outward movement of the leg, whereby when the leaves are folded the central portion of the table and the ironing board form a continuous operating surface of substantially 40 the same width, or when said leaves are supported by their legs the operating surface beyond the ironing board is of greater width than the latter.
